ROTARY SLIDING VANE PUMP STRUCTURE

Alfred L. Stamsvik, Pittsburgh, Pa.

Application July 29, 1943, Serial No. 496,528

4 Claims. (Cl. 103—137)

1

This invention relates to apparatus for pumping liquid and more especially liquid such as milk, a service that requires repeated and thorough cleaning of the pump.

Because of the high standard of cleanliness required of milk pumps, any type of pump that cannot be easily and thoroughly cleaned is not suitable for the purpose. Centrifugal pumps have been widely used, but have the disadvantage of low delivery pressure. One of the practical difficulties in using force pumps has been the fact that stuffing boxes cannot be adequately cleaned.

It is an object of this invention to provide an improved pump suitable for milk. The invention is particularly concerned with the construction of the pump rotor and the stuffing box or seal for preventing the milk, or other liquid, from leaking out of the pump around the drive shaft. The packing of this invention is combined with a vane pump to produce a pump structure that delivers the milk against substantial pressure but can be disassembled easily and has no recesses that are not readily accessible for cleaning.

With this invention the pump vanes slide in a slot that extends completely through the rotor so that there are no pockets in the rotor. The drive shaft of the pump extends out through a recess in one wall of the housing. The recess opens toward the interior of the housing and holds a sealing ring that is kept under pressure by a spring in the recess. The sealing ring and spring are removed with the pump rotor for cleaning and the recess in the housing is large enough to be easily cleaned at the same time as the interior of the housing.

Other objects, features and advantages of the invention will appear or be pointed out as the specification proceeds.

In the drawing:

Fig. 1 is a central, sectional view, with some parts in elevation, showing a pump embodying this invention;

Fig. 2 is a sectional view on the line 2—2 of Fig. 1; and

Fig. 3 is a sectional view, with some parts broken away, the section being taken on the line 3—3 of Fig. 1.

The pump includes a housing 10 having an inlet 11 and outlet 12 that communicate with a cylindrical chamber 13 within the housing 10. The entire front end of the chamber 13 is closed by a plate 14 (Fig. 1) that is clamped against a gasket 15 on the rim of the housing by wing nuts

2

16 that thread on stud bolts 17 extending from the housing 10.

There is a recess in the back wall 20 of the chamber 13. The recess is large enough for easy access when cleaning the pump, and has a cylindrical side wall 21 and an end wall 22. The axis of the cylindrical wall 21 is parallel to but eccentric of the axis of the chamber 13.

The pump has a rotor 23 that extends the full length of the chamber 13. A hub 24 of the rotor 23 turns in the recess with the cylindrical side wall 21 as a bearing. Vanes 25 slide in a diametrical slot or groove 26 (Fig. 2) that extends all the way through the rotor without change of width so that the surfaces of the groove are free of any corners. The groove 26 opens through the front end of the rotor to further facilitate cleaning. The vanes 25 are urged radially by a spring 27, and with the spring 27 are removable from the rotor without disconnecting any fastening means. There are shallow recesses 31 at the inner ends of the vanes for preventing transverse displacement of the spring 27.

The driving connection for the pump includes the hub 24 and a drive shaft 29 that is connected to and in axial alignment with the hub. The drive shaft 29 preferably extends through the end wall 22 as a bearing and has an end 30 shaped for coupling with a source of power. The hub 24 being of considerably larger diameter than the shaft 29 provides a shoulder 32 at the end of the shaft.

An annular sealing ring 33 fits snugly around the shaft 29. The outside diameter of the sealing ring 33 is the same as that of the cylindrical wall 21 and the ring 33 prevents liquid from leaking along the bearing surface 21 beyond the shoulder 32.

The sealing ring 33 is held against the shoulder 32 by a coil spring 34 compressed between the end wall 22 and a washer 35 that bears against the back of the sealing ring 33. In the preferred embodiment of the invention all parts of the pump are of stainless steel, except the sealing ring 33 and that ring is made of rubber, preferably soft rubber.

The washer 35 has a sloping face in contact with the sealing ring for developing some radial thrust of the sealing ring 33 inward against the shaft 29. During operation of the pump, the sealing ring 33 remains stationary while the surfaces of the shoulder 32 and shaft 29 that are in contact with the sealing ring move with respect to the ring. These surfaces are sufficiently extensive to effectively seal the pump against

leakage of milk even though the pressure of the sealing ring on the metal surfaces is light. Tendency for milk to leak inward along the shoulder 32 is less than if the direction of leakage were radially outward.

It will be apparent that removal of the cover plate 14 permits the other elements of the pump to be disassembled completely without disconnecting any other fastening means. All of the removable parts of the pump come out through the opening in the front end of the housing. The ease with which the pump can be disassembled is important in a milk pump that requires frequent and thorough cleaning.

After the various elements of the pump have been cleaned, the apparatus can be reassembled with the same facility with which it was taken apart. The spring 34 is first inserted in the recess in the back wall of the housing. The washer 35 is inserted next, and then the sealing ring 33. The vanes 25 are put in the slots 26 of the rotor 23 with the spring 27 between them. The vanes are pushed toward one another to compress the spring 27 and to reduce the combined radial extent of the vanes to something less than the diameter of the chamber 13. The shaft 29 is then pushed through the chamber 13, through the recess in the back wall 20 and through the openings in the sealing ring 33, washer 35, spring 34, and end wall 22. At the same time the hub 24 is pushed into the bearing 21 and the rotor 23 into the chamber 13 until the side of the rotor contacts with the back wall 20. The parts are then held in assembled relation by putting the plate 14 over the end of the housing and fastening the plate in place with the nuts 16.

Terms of orientation are, of course, relative. The illustrated embodiment of the invention can be modified, and some features of the invention can be used without others.

What is claimed is:

1. A pump comprising a housing in which is a cylindrical chamber, said housing including a removable cover closing the front end of the chamber, the walls of the chamber being straight and free of depressed regions so that the cover forms the entire front wall of the chamber, a rotary pump element in the chamber, a rearwardly extending hub on said pump element, a drive shaft connected with the hub of the pump element and coaxial with, but of smaller diameter than the hub so that there is a shoulder at the end of the shaft, an inside cylindrical bearing surface for said hub on a wall of the housing, an annular sealing ring beyond said hub and in sealing contact with both the outside surface of the shaft and said cylindrical bearing surface, and a spring urging the sealing ring against the shoulder, said pump element, drive shaft, sealing ring and spring being removable through the front of the housing when the cover is removed.

2. A milk pump including a housing in which is a large-diameter cylindrical chamber, inlet and outlet conduits having straight and smooth walls and opening directly into the cylindrical chamber, a front plate that covers the end of the cylindrical chamber, the wall of said chamber being straight and free of depressed regions so that said plate comprises the entire front wall of the chamber, said plate being removable to expose the interior of the pump for cleaning, a cylindrical opening through the back wall of the chamber having an axis eccentric of but parallel to the axis of the cylindrical chamber, a rotor that extends along the full length of the chamber-

ber and that is held against endwise displacement by the front and back walls of the chamber, vanes carried by the rotor, a hub extending from the rotor and fitting into the cylindrical opening as a bearing, a drive shaft connected with the hub and coaxial with the hub, said drive shaft being of smaller diameter than the hub so that there is a shoulder at the connection of the drive shaft and the hub, said rotor, hub and shaft being removable through the front of the housing when the front plate is removed, packing means that is also removable with the rotor, hub and shaft, said packing means including a sealing ring surrounding the shaft and in sealing contact with both the surface of the shaft and the cylindrical bearing surface of the opening, a washer at the back of the sealing ring for holding the sealing ring against said shoulder, said washer having a bevel face in contact with the ring, a spring around the shaft, and a surface at the rearward end of the cylindrical bearing for holding the spring compressed against the washer.

3. A milk pump including a housing in which is a large-diameter cylindrical chamber with substantially straight inlet and outlet connections angularly related and located around the periphery of the cylindrical chamber, a plate that covers the end of the cylindrical chamber, the wall of said chamber being straight and free of depressed regions so that said plate comprises the entire front wall of the chamber, said plate being removable to expose the interior of the pump for cleaning, a cylindrical opening through the back wall of the chamber having an axis eccentric of but parallel to the axis of the cylindrical chamber, a rotor that extends along the full length of the chamber and that is held against endwise displacement by the front and back walls of the chamber, vanes carried by the rotor, a hub extending from the rotor and fitting into the cylindrical opening as a bearing, said rotor having a diametrical slot in its front face, which slot extends for the full length of the rotor from said hub, the side walls of said slot providing guide bearings in which the vanes slide, a spring in the slot between the inner ends of the vanes and urging the vanes outward against the cylindrical side wall of the pump chamber, a drive shaft connected with the hub and coaxial with the hub and rotor, and a sealing ring in the cylindrical opening beyond said hub and around said shaft, said ring being removable with the shaft through the front of said opening for convenient cleaning.

4. A pump for milk or other beverage that requires thorough and frequent cleaning of the pump, said pump including a housing with a cylindrical chamber that has a rearward wall in which there is a cylindrical recess of substantial diameter having an axis eccentric of but parallel to the axis of the pump chamber and a central opening through the back wall of the recess, a rotor having a length substantially equal to that of the cylindrical chamber and a diameter less than that of the cylindrical chamber but greater than that of the recess, a hub at the back of the rotor and secured to the rotor, said hub having a diameter equal to that of the recess and fitting into the recess as a bearing but not extending for the full length of the recess, a drive shaft smaller than the hub and extending from the hub through the central opening in the back wall of the recess, sealing means in the recess and around the shaft, said sealing means being re-

movable from the housing with the rotor and shaft through the front of the housing for convenient cleaning, guides comprising a groove that extends across the rotor, said groove being of substantially uniform width and open to the front of the rotor, vanes that slide in the groove, a spring in the groove between the vanes for thrusting the vanes against the cylindrical wall of the pump chamber, a cover plate closing the cylindrical chamber and forming the front wall 10 of the pump chamber, and detachable fastenings securing the cover plate to the housing.
